UNITED STATES PATENT OFFICE.

WILLIAM L. FODREA, OF LITTLE ROCK, ARKANSAS, ASSIGNEE TO DAN DANIEL, OF LITTLE ROCK, ARKANSAS.

COTTON-PICKING MACHINE.

1,247,387.

Specification of Letters Patent. Patented Nov. 20, 1917.

Application filed December 30, 1916. Serial No. 139,346.

To all whom it may concern:

Be it known that I, WILLIAM L. FODREA, a citizen of the United States, and a resident of Little Rock, in the county of Pulaski and State of Arkansas, have invented certain new and useful Improvements in Cotton-Picking Machines, of which the following is a specification.

My invention is an improvement in cotton picking machines, and has for its object to provide a machine of the character specified, consisting of a wheeled support which may be driven through the field, and which is provided with exhausting apparatus, with flexible hose for receiving the cotton as it is picked, and wherein other mechanism is provided for positively removing the cotton from the boll and delivering it to the exhausting mechanism.

20 In the drawings:

Figure 1 is a rear view of the improved picker,

Fig. 2 is an enlarged detail with parts in section,

25 Fig. 3 is a side view of the means for positively removing the cotton,

Fig. 4 is a perspective view of the same, and

30 Fig. 5 is a perspective view of the supporting harness for the hose.

In the present embodiment of the invention a receiver 1 is provided for the cotton, in the form of a closed wagon box, and the said receiver is supported for movement by the wheels 2 which are connected to the body or receiver by arched axles 3. A suitable motor 4 is mounted in rear of the receiver, and this motor drives an exhausting device 5, the said device being in the form of a fan 40 and delivering to the receiver. A main pipe 6, is supported transversely of the receiver above the same, and the said pipe is connected intermediate its ends to the fan or exhausting device by means of a vertical pipe 7. The ends of the pipes 6 are closed by screw threaded plugs 8, as shown in Fig. 2, and the said pipe is provided with elbows 9, the said elbows being six in number in the present instance, and a flexible 45 hose 10 is connected with each elbow.

A shaft 11 is journaled parallel with the pipe below the same in bearings 12 which are connected with the pipes by suitable collars 13 connected with the bearings, and this 50 shaft is provided at each elbow with a bevel

gear 14. A U-shaped bracket 15 is mounted on the shaft at the outermost bevel gears, each bracket having bearings at its ends for engaging the shaft on opposite sides of the gear, and having a central bearing 16 in 60 which is journaled a flexible shaft 17, and each flexible shaft has a bevel gear 18 meshing with the adjacent gear 14. At the intermediate bevel gears, double brackets 19 are arranged, each of the said brackets being 65 approximately W-shaped and having three bearings 20 journaled on the shaft, one of the said bearings being between adjacent bevel gears, and the other bearing being outside of the said gears. Each of these 70 brackets 19 has a vertical bearing 21 between each pair of shaft engaging bearings, and a flexible shaft 17 is journaled in each of the bearings 21, each flexible shaft having a bevel gear 22 engaging the 75 adjacent gear 14.

Each of the hose 10 branches at its ends into branches 23 and 24, and the flexible shaft 17 follows the branch 24. The branching is brought about by a Y-shaped nipple 80 25 having its body portion connected with the main hose 10 and its arms connected with the branches. The branch 23 of each hose has a funnel shaped nozzle 26, and the end of each branch 24 is provided with picking mechanism to be later described in detail. It will be noted from an inspection of Figs. 2 and 5, that the flexible shaft is connected to the hose and branch by clips 27, the said clips being arranged at suitable intervals, and engaging both hose and shaft.

A suitable harness is provided for supporting the branches on the shoulder of the cotton picker. This harness comprises a belt 28 adapted to pass about the waist of 95 the wearer and having a buckle 29 and a tongue 30 for securing it in place. At the rear is a strap 31 and a buckle 32, and the strap is adapted to be passed about the hose at the Y. The shoulder straps 33 are connected with the belt at the rear, and are adapted to be connected with buckles 34 at the front. The branches 23 and 24 are passed over the shoulders of the wearer, and the branch 23 has straps 35 connected therewith, which are adapted to be buckled about the left arm of the user, as shown more particularly in Fig. 1. The branch 24 may also be provided with straps for the same purpose.

The picking mechanism shown in Figs. 3, 4 and 5, comprises a nozzle 36 fitting over the end of the hose and having an enlarged portion 37. This enlarged portion is circular in cross section, and is sectional, and an annular inwardly facing channel is provided at the periphery thereof. Within this channel is mounted a series of picking wheels 38, the planes of the wheels being radial to the nozzle, and each wheel is secured to the stub shaft 39. The stub shafts of the adjacent wheels are connected to connecting shafts 40 by universal joint connections, and these shafts 40 are journaled in bearings 41 arranged about the opening through the nozzle. The flexible shaft 17 is connected to one of the stub shafts 39, as shown in Fig. 4, and it will be obvious that when the shafts are rotated, all of the wheels will be rotated, and they are rotated in a direction such that at their inner sides they will move inward. It will be noticed that there are five picking wheels and each wheel is opposite the space between two wheels. The present machine is arranged to permit the picking of three rows at a trip across the field, and six pickers are provided for the three rows, two pickers working on each row. By means of the harness the hose is supported on the picker with one of the branches on each arm. The picker separates the cotton from the boll and it is drawn through the branch 23 into the receiver with the nozzle, shown in Fig. 4, the wheels picking the cotton, and it is drawn through the hose into the receiver. The wheels are toothed as shown, and the

teeth engage the cotton in the boll and pull the same from the boll, the air suction in the tube removing the cotton from the teeth and drawing it into the receiver.

40

I claim:

1. A cotton picker comprising a wheel supported receiver, a pipe supported transversely of the receiver above the same and having depending nipples, means for exhausting the air from the pipe and delivering the said air to the receiver, flexible hose connected with the nipples, each hose branching at the end remote from the pipe, one of the branches having a flaring nozzle, and the other branch having mechanical means for positively picking the cotton, and a common driving means for all of the said picking means, said driving means comprising a shaft supported by the pipe below the same, means for driving the shaft and the exhausting device, flexible shafts at the nipples and driven by the first named shaft and connected with the picking mechanism.

2. In a cotton picker, the combination with a receiver, of hose pipes, each pipe branching at the end remote from the receiver, one of the branches having a flaring nozzle, and the other having mechanical means for positively picking the cotton, and means for exhausting the air from the hose pipes.

WILLIAM L. FODREA.
